Inventor.

Mesworth D. Drake.

United States Patent Office.

MEXWORTH D. DRAKE, OF SCITUATE, ASSIGNOR TO W. E. BARRETT, OF PROVIDENCE, RHODE ISLAND.

Letters Patent No. 91,613, dated June 22, 1869.

IMPROVEMENT IN PITMEN.

The Schedule referred to in these Letters Patent and making part of the same.

Know all men by these presents:

That I, MEXWORTH D. DRAKE, of Scituate, in the county of Providence, and State of Rhode Island, have invented certain new and useful Improvements in Pitman-Connections for Harvesters, of which the following is a full, clear, and exact description, reference being had to the accompanying drawings, forming a part of this specification, in which—

Figure 1 represents a perspective view of my improved pitman-connection;

Figure 2 represents a longitudinal central section on the line B B, fig. 1; and

Figure 3 represents a longitudinal section through the device shown in fig. 1, on the line A A, fig. 2.

To enable those skilled in the art to which my invention belongs, to make and use the same, I will describe it more in detail.

In the drawings—

A represents the outer end of the pitman-rod, which is provided with a head, B, which fits in a recess in the inner part C of the connection D.

On top of head B is placed a metal strip, a, and on top of that is placed a bushing, or bearing E, composed of strips b of raw hide; said bushing or bearing-pieces being cut out to fit the crank-pin F.

Another bearing, G, composed of strips of raw hide b, is fitted in the outer part H of the connection D, its inner face being cut out to fit the crank-pin F.

A metal strip, c, is placed between the bushing, or bearing-piece G and the part H, as fully shown in the drawings.

The parts C and H are provided with ear-pieces I I and J J, for the reception of the screw-bolts K K, by means of which the parts C and H of the connection D are drawn closely together, thereby causing the bushings, or bearing-pieces E and G, to clasp the end of the crank-pin, as fully indicated in the drawings.

The outer sides of the parts C and H are made with projections d, for the reception of the head L of the crank-pin F, as shown in fig. 2.

It will be seen that the inner face of head L has a bearing against the ends of the raw-hide bushing, or bearing-pieces E G, so that the wearing parts of the crank-pin F work against the raw-hide bearing-pieces, thereby rendering the connection more durable, and less liable to wear than the ordinary connection in which the bearing-parts of the connection are made of Babbit metal.

To prevent any rattle, and also to compensate for any wear of the crank-pin or the raw-hide pieces, a

set-screw, M, having a set-nut, O, is fitted to the stem N, whereby, when the set-screw M is screwed in, its point will press against the metal strip c, thereby forcing the bearing-piece G against the crank-pin F sufficiently to prevent too much play between the raw-hide pieces and the crank-pin.

After set-screw M has been turned down far enough, set-nut O is turned back against the stem N, thereby locking the screw securely in place.

The long thimble P, on the inner end of the part C, affords such a support to the outer end A of the connecting-rod, as to prevent all binding or injurious twisting of the head in its socket.

The metal a prevents head B from wearing the piece E of raw hide.

The pieces C and H of the connection D fit together so closely that dust and dirt are effectually excluded from the rubbing and bearing-parts of the bushing or crank-pin, thereby rendering the connection peculiarly adapted for use in harvesting-machines.

The raw-hide washer Q, upon the inner end of the crank-pin, as shown in fig. 2, prevents dust and dirt working in between the inner edges d' of the parts C and H, and the crank-pin F.

As it may be desirable to introduce some lubricating-substance occasionally, a screw, e, is fitted to the connection D on a line with the space f, between the raw-hide pieces E and G, as indicated in the drawings, whereby oil, or other lubricating-substances, can be turned in by simply removing screw e.

Great difficulties have arisen from the wearing and heating of the pitman-connections heretofore in use in harvesting-machines, and my present improvements are designed to obviate and remedy the same.

Having described my improved pitman-connection for harvesters,

What I claim therin as new, and desire to secure by Letters Patent, is—

1. The combination, with the parts C and H, and means for holding said parts together, of the raw-hide bearing-pieces E G, substantially as and for the purposes set forth.

2. The combination, with the parts named in the preceding clause, of the metal pieces a and c, set-screw M, and set-nut O, substantially as and for the purposes set forth.

MEXWORTH D. DRAKE.
